UNITED STATES PATENT OFFICE.

GEORGE ALLEN SEELEY, OF IRVINGTON, NEW JERSEY, ASSIGNOR TO WESTERN ELECTRIC COMPANY, INCORPORATED, OF NEW YORK, N. Y., A CORPORATION OF NEW YORK.

PRESS.

Application filed April 30, 1927. Serial No. 187,997.

This invention relates to presses, and more particularly to guards for metal extruding presses.

It is an object of this invention to provide 5 a guard for a press which is effective from the standpoint of protection and does not interfere with the normal operation of the press.

The invention contemplates the provision 10 of a guard to surround the plunger of a metal extruding press, such as a cable sheathing press, when the plunger first comes in contact with the metal in the extruding cylinder. In accordance with one 15 embodiment of the invention a guard is provided which may be placed around the plunger at the beginning of the extruding operation and upon a predetermined relative movement between the plunger and cylinder, the guard is automatically removed to a position where it will not interfere with the further movement of these parts.

It is believed that a complete understanding of the invention may be had by reference 20 to the following description taken in conjunction with the accompanying drawing, illustrating one embodiment of the invention and in which:

Fig. 1 is a front elevation of an extruding press provided with a protective guard;

Fig. 2 is a fragmentary view thereof showing the guard in another position removed from the plunger, and

Fig. 3 is a fragmentary plan sectional view taken on the line 3—3 of Fig. 1.

Referring to the drawings in which the same reference characters represent similar parts in the several views, the invention is 35 illustrated as embodied in a lead or lead alloy extruding press of the type commonly used in covering cables for use in telephone communicating systems.

The frame of the machine consists of columns 5 which support a beam 6 upon which 40 a plunger 7 of the press is mounted. A cylinder 8 is carried upon a ram 9 by means of which the cylinder may be raised or lowered by a suitable hydraulic pressure system (not shown). In order to fill the cylinder with molten lead or alloy the cylinder is lowered until the plunger is removed therefrom and the molten metal is then poured into the cylinder until the cylinder is slightly overflowed with the upper surface 45 of the surplus projecting slightly above

the top of the cylinder. This is done to insure that there will be no air between the lead and the plunger which might cause blisters in the extruded cable covering. Before the metal is extruded it is cooled under pressure and the cylinder is therefore raised to bring the plunger into pressing engagement with the top surface of the metal. If the cylinder is raised too quickly before the plunger enters the cylinder the molten interior 50 of the metal may tend to burst through the solidified exterior shell thereof and project hot metal in the vicinity of the press and endanger the workmen. After the metal has been cooled under pressure a sufficient length of time, it may be safely extruded in the usual manner through an opening 10 around a cable 11.

In order to protect the workmen against this danger, a pair of semi-circular guarding members 12 are provided, each supported by an arm 14 pivoted at 15 in an arm support 16 which is attached to one of the columns 5. The opposite end of the arm 14 is provided with a counterweight 18 to 55 balance the weight of the guard member 12. When a charge of molten metal has been placed in the cylinder 8 the guard members are placed by the operator in the positions shown in full lines in Fig. 1. As 60 the cylinder is raised it will raise the guards and finally engage the arms 14 raising the guard members 12 until the positions shown in dotted lines in Fig. 1 are 65 reached, when the counterweights 18 will 70 overbalance the weight thereof and move them into the position shown in Fig. 2 where they will not interfere with the further movement of the cylinder. In order 75 to prevent the guard members 12 from 80 striking the columns 5, each arm 14 is provided with a pin 19 which travels around the circular end portion of the arm support 16 until it reaches the end of the arc 85 when it will engage the flat upper surface 90 of the arm and prevent further movement of the guard member. The balanced effect 95 obtained by the use of the counterweights 18 is also of advantage in restraining the movement of the guard members 12 toward 100 the cylinder head so that when the guard is placed in position by the operator the guard members will not strike the cylinder head with any such impact as would tend 105 to mar the cylinder head or the guard mem- 110

bers. By properly adjusting the positions of the guard supports 16 upon the columns 5 the movements of the guard members may be properly timed to afford the desired protection under a wide variety of operating conditions.

It will be understood that the embodiment of the invention herein described and illustrated is merely a convenient and useful 10 form of the invention which is capable of many other modifications without departing from the spirit and scope of the invention.

What is claimed is:

- 15 1. In a press having a relatively movable cylinder and plunger, a protective guard normally disposed in the path of said relatively movable parts, and means for withdrawing the guard from the path of the 20 movable parts upon a predetermined relative movement between the parts.
- 25 2. In a press having a relatively movable cylinder and plunger, a guard support stationary with respect to one of said members, a guard member carried by an arm pivoted in said support, and means for removing the 30 guard member from its guarding position upon a predetermined movement between the cylinder and the plunger.
- 35 3. In an extruding press having a relatively movable cylinder and plunger, a guard support stationary with respect to one of said members, an arm pivoted on said support, a guard member secured to one end 40 of the arm and a weight secured to the other end of said arm, said weight being so positioned with respect to the guard member that when the guard member is raised a predetermined distance it will be overbalanced by the weight.
- 45 4. In an extruding press having a relatively movable cylinder and plunger, a guard support stationary with respect to one of said members, a guard member carried by an arm pivoted in said support, means for

removing the guard member from its guarding position upon a predetermined movement between the cylinder and the plunger, and means for limiting the movement of the guard member.

5. In an extruding press having a relatively movable cylinder and plunger, a guard support stationary with respect to one of said members, a guard member carried by an arm pivoted in said support, means for removing the guard member from its guarding position upon a predetermined movement between the cylinder and the plunger, and a pin in the arm carrying the guard adapted to engage the support to limit 60 its movement.

6. In an extruding press having a relatively movable cylinder and plunger, a pair of semi-circular guard members for surrounding the plunger at the beginning 65 of an extruding operation, means for pivotally supporting the guard members at opposite sides of the press, and means for moving the guards about their pivot and away from the plunger upon a predetermined relative movement between the cylinder and plunger.

7. In an extruding press having a relatively movable cylinder and plunger, a guard for limiting the escape of material 75 from the press, and means controlled by a relative movement of the cylinder and plunger for limiting the period of effectiveness of the guard.

8. In an extruding press having a relatively movable cylinder and plunger, a guard for limiting the escape of material from the press, and means responsive to a relative movement between the cylinder and plunger for removing the guard from its 80 operative position.

In witness whereof, I hereunto subscribe my name this 20th day of April A. D., 1927.

GEORGE ALLEN SEELEY.
